*L.L. Gilliland,
Making Matches.*

N° 8,069.

Patented Apr. 29, 1851.

UNITED STATES PATENT OFFICE.

LEWIS L. GILLILAND, OF DAYTON, OHIO.

SPLINT-MACHINE.

Specification of Letters Patent No. 8,069, dated April 29, 1851.

To all whom it may concern:

Be it known that I, LEWIS L. GILLILAND, of Dayton, in the county of Montgomery and State of Ohio, have invented certain new and useful Improvements in Machines for Forming Match-Splints; and I do hereby declare that the following is a full, clear, and exact description of my said invention, reference being had to the accompanying drawing, which forms part of this specification, and in which—

Figure 1 represents a view in perspective of my rotary match splint machine and Fig. 2 is a plan of the same.

15 My invention consists first in splitting and pointing match splints by knives secured to a continuously revolving wheel, which is also fitted with a circular screw formed gage plate, which revolves with the 20 knives, and gages the breadth of the splints.

The second portion of my invention consists of an apparatus for holding the block of which the match splints are formed and presenting it to the splitting, pointing, and 25 gaging apparatus in such manner that the grain of the wood, where the splitting knives are acting upon it, shall always be held in line with the plane in which the knives revolve; so that they may split the 30 block, without cutting across the grain, whether the latter be at right angles or oblique to the sides of the block.

In the accompanying drawing A is the bed of the machine to which the other portions are secured. Two standards B, B, are mounted upon this bed to support the boxes in which the mandrel C of the cutter wheel D revolves. This mandrel is fitted with a belt pulley e to which a belt is applied, 40 by means of which it is caused to revolve with great speed. The cutter wheel D is firmly secured to the mandrel C and has a circular disk f secured to its face. This disk is notched at those parts where the knives 45 are to be placed. The latter are of two kinds, the one for splitting, and the other for pointing the splints, and are arranged in pairs at the notched portions of the disk f. The splitting knife g, whose edge is 50 straight, is of triangular form, its point projecting outwards beyond the rim of the disk. The other knife h is secured to the face of the disk f immediately behind the splitting knife; this second knife is hooked is shown 55 at Fig. 1 and its edge is bent outward from the face of the splitting knife as shown at

Fig. 2. The outer end of this curved knife projects but slightly beyond the rim of the disk, it follows in the track of the splitting knife and shaves off the wood to form the 60 points of the splints. That portion i of the disk f, immediately preceding the edge of each splitting knife, is bent backward from the face, as shown at Fig. 2, in such manner that the space between the hinder face of 65 the splitting knife and the face of this bent portion of the disk shall be equal to the thickness of the match splints to be formed.

The apparatus for holding the block consists of a stock J which rests upon a stationary support or pillow K that is firmly secured to the bed A. This stock has a groove formed in its upper face of sufficient size to receive the block M of which the splints are formed, and is fitted with a sliding bar L, 70 or driver, which slides in the groove, bears against the end of the block, and causes the latter to bear against the face of the disk f. This driver is drawn forward, or toward the face of the disk f, by means of a weight N, 75 which hangs beneath the bed A, and is connected with the driver L by means of a cord o, which is passed through an aperture in a standard P. The latter is projected upward immediately in front of the face of the disk 80 f, its edge being just far enough therefrom to allow the knives to pass freely. This standard acts as a support and guard to steady the block while the knives are acting upon it. A portion of the outer side r of the 85 groove is removed and its place is supplied by a wedge formed block or clamp s, which is pressed toward the guard P by means of a spring t. The guard P stands in such a position that its edge is a little within the 90 rim of the disk f, and the inner side of the groove in the stock J is in line with this edge, so that as the block M is forced forward a narrow portion of its extremity, 95 equal in width with the horizontal distance 100 of the edge of the guard P from the periphery of the disk f, bears against the latter.

The stock J has two concentric circular slots, shown in dotted lines in Fig. 2, formed in its inner face, and two pivots (also shown in dotted lines in Fig. 2) are secured to the upper face of the pillow K and enter the circular slots of the stock J, when the latter is placed upon the pillow. The pins are placed in the arc of a circle whose center 105 is in the line in which the edge of the splint, block M touches the face of the disk f.

These pivots, in connection with the slots of the stock, prevent the latter from being moved endwise, but allow it to be turned sidewise to turn the block to the position in 5 which the grain is parallel with the plane in which the splitting knives revolve.

The operation of this machine is as follows. The cutter wheel is caused to revolve rapidly in the direction indicated by 10 the arrow *u* in the drawing, by means of the belt applied to the belt pulley *e*. The driver *L* is then drawn backward in the groove of the stock *J* and the block of which the splints are to be formed is inserted 15 between its end and the face of the disk. The driver is now allowed to bear with the force of the weight *N* against the block, which is shoved endwise against the disk, being at the same time held firmly in 20 contact with the guard *P* by the action of the spring clamp *s*. As the disk *f* revolves the bent portions *i* pass the block, which, being pressed endwise by the driver, is fed forward a distance equal to the recession 25 of this bent portion, which is equal to the thickness of the splint, and is thus brought within the range of the knives. The splitting knife *g* first strikes the wood and splits it, while the pointing knife *h*, following in 30 the track of the splitting knife, shaves off a small portion of the solid block at the margin of the split; the rim of the disk *f* follows in the track of the pointing knife, and thus prevents the block from being fed 35 forward until the next bent portion of the disk enters the split in the block which is again fed forward and again split by the succeeding knives. As fast as one block is split a new one is inserted in its place. 40 And as each block is being split the edge of the disk and the splitting knives turn the stock *J* to such a position as will allow the splitting knives to act in the direction of the grain of the wood whether that be 45 perpendicular or oblique to the face of the block. By the above process the blocks are split and shoved in but one direction. Each

split block is now broken into square pieces which are introduced in the machine and split at right angles to the direction in 50 which the first splits were made; as the pointing knife follows the splitting knife the wood, which has already been split into thin slabs and shaved in one direction, is now split and shaved at right angles to that 55 direction, by which means the thin slabs formed by the first splitting are subdivided into square splints sufficiently pointed and ready for dipping, which operation may be performed in any approved manner. 60

As wood when treated by this machine is liable to be split entirely through by the action of the splitting knives I prepare the blocks by glueing a piece of cotton cloth to their backs before they are split. This 65 cloth holds the splints together and enables the operator to handle them with facility without danger of breaking the splints apart.

The machine represented in the accompanying drawing is fitted with two sets of knives; this number may be increased if deemed advisable, care being taken to increase the diameter of the disk *f* in a proportionate degree. 70

What I claim as my invention and desire to secure by Letters Patent is—

A cutter wheel constructed substantially as herein set forth to split, point, and gage the size of match splints, in combination 80 with the method of preventing the splitting knives from cutting across the grain of the wood by supporting the block upon a stock is constructed to turn as herein set forth to present the grain of the wood, where the 85 splitting knife is acting, in line with the plane in which the knives revolve.

In testimony whereof I have hereunto subscribed my name.

LEWIS L. GILLILAND.
